P. VACATOS

REFRIGERATOR

Filed May 16, 1922

Inventor
Perry Vacatos

By *F. E. Shannon*

Attorney

UNITED STATES PATENT OFFICE.

PERRY VACATOS, OF AKRON, OHIO.

REFRIGERATOR.

Application filed May 16, 1922. Serial No. 561,371.

To all whom it may concern:

Be it known that I, PERRY VACATOS, a citizen of the United States, residing at Akron, in the county of Summit and State 5 of Ohio, have invented new and useful Improvements in Refrigerators, of which the following is a specification.

This invention relates to certain new and useful improvements in refrigerators and 10 has particular reference to an ice-box for preserving live sea foods.

Objects of the invention are to provide an ice-box of simple, durable construction, having a storage space arranged to be surrounded with ice and to provide in combination therewith new and novel means for supporting articles therein, whereby the same will be conveniently accessible and whereby a large quantity of sea food may 20 be stored without crowding in a relatively small space.

A further object is to provide a box of the class above indicated, and to provide in connection therewith means whereby the interior thereof may be ventilated and in which lobsters, crabs or other sea food of a similar nature may be kept alive for a relatively long period of time.

The above and additional objects are accomplished by the novel construction, combination and arrangement of parts herein-after described and illustrated in the accompanying drawing in which I have shown a preferred embodiment of the invention, it being understood that changes and modifications may be made or substitutions resorted to which come within the scope of the claims hereunto appended.

In the drawings in which similar numerals of reference have been employed to designate similar or like parts as the same may appear in each of the several views and in which:

Figure 1 is a perspective view of an ice-box constructed in accordance with this invention and showing the front portion thereof cut away to illustrate a cross sectional view taken on line 1-1 of Figure 3.

Figure 2 is a perspective view of one of the trays employed in carrying out this invention.

Figure 3 is a horizontal, sectional view taken approximately on line 3-3 of Figure 1.

Proceeding now to a detailed description of the invention with reference to the accompanying drawing in which I have shown a rectangular box 3 having a bottom wall 4 and side walls 5, 6, 7 and 8. The numeral 10 denotes a cover which is suitably hinged to the rear wall 7. The side walls are provided at the upper edge thereof with the rabbet 10^a which extends longitudinally thereof along the inner edge thereof and provides a seat for the cover 10. The cover 10 is rabbeted along the outer edge thereof and is adapted to fit in the rabbet 10^a with the outer edge thereof flush with the outer face of said side walls. The cover 10 is provided with a large rectangular opening 11 which is centrally positioned therein and the said cover is rabbeted around the edge of said opening to receive the rabbeted edges of the lid 11 which is hinged to the cover 10 so as to close the said opening. The lid 11 and the sides and bottom of the box are provided with the cavities 12 which are filled with mineral wool, charcoal or other insulating material.

The numeral 13 denotes an inner casing or lining which is in the form of a box of substantially the same proportions as the box 3 hereinbefore described, but is relatively smaller. The lining 13 is preferably composed of metal, but may be composed of any suitable material and the same is nested in a central position within the box 3 with its sides in parallel spaced relation to the similar sides of the box 3, thus forming between the walls of the box 3 and the casing 13 an ice space 14. The numeral 15 denotes cleats which are positioned on the bottom 4 to support the lining 13 with the bottom wall thereof in spaced relation to said bottom 4. The lining 13 is enlarged at the upper end thereof to form, on the inner side thereof, the shoulder 16 which extends entirely therearound and provides a support for the ice pan 17. The ice pan 17 is formed to fit within the enlarged upper portion of the box 14 and is provided with the drain opening 18 which communicates with the opening 19 in the lining 13 which is formed therein at a point in the shoulder 16 to provide a drain whereby water from the ice in the pan 17 may pass to the ice space 14. The inner casing 13 extends upwardly to the cover 10 which is arranged to cover the ice space 14. The opening in the cover 10 is approximately the same size and conforms in shape to the upper end of the lining 13 so that the ice pan 17 may be removed when

the lid 11 is opened, without opening the cover 10.

A plurality of trays 20 are arranged to be placed in superposed relation in the casing 13. Each tray 20 is formed with the heavy frame work 20^a and has side walls and bottom walls of wire screen or other suitable open work material. Each tray 20 is provided at opposite ends thereof with the handles 20^c which are suitably secured to the inner edge of the top bar of the frame work 20^a so that the same may be moved to an upright position to furnish means whereby the tray may be conveniently handled or folded within the tray when the said trays are positioned within the casing 13. The casing 13 is provided with the plurality of openings 21 which are distributed in relatively close spaced relation over the entire area thereof. The sides 6 and 8 of the box 3 are provided with a plurality of openings 22 and the inner casing 13 is provided at a point in alignment with each of said openings with a similar opening 24. The numeral 23 denotes a ventilating pipe 10 mounted in the openings 22 and 24 so as to extend across the ice space 14 as shown in Figure 3. The numeral 25 denotes a cover plate which is hinged to the side walls of the box 3 at a point adjacent each opening 22 and is arranged so that the opening 22 may be closed or partly closed thereby as illustrated in Figure 1.

To use my improved ice box, the cover 10 is opened and the space 14 is filled with ice. The desired quantity of live lobsters or other crustacea is placed in the trays 20 and the said trays are placed in superposed relation within the casing 13 as shown in Figure 1.

The ice pan 17 is filled with ice and placed in position on the shoulder 16 so as to close the upper end of the casing 13. The covers 25 are then operated to regulate the size of the opening 22 and provide proper ventilation. When the trays 20 are properly positioned in the ice-box, the frame work of the upper trays rest upon the frame work of the trays directly therebeneath, the handles 20^c being turned downwardly to avoid interference with the tray directly above.

Access may be had to the upper tray 20 by

opening the lid 11 and removing the ice pan 17 and all of the trays 20 may be removed without opening the lid 10. The openings 21 in the casing 13 permit the air within the casing to contact directly with the ice and a moist, cold atmosphere is thus maintained.

It will thus be seen that I have provided a new and improved ice-box which in use will provide convenient means whereby a large quantity of sea food may be kept alive for a considerable time.

Having thus described my invention, what I claim as new and desire to secure by Letters-Patent is:—

1. A refrigerator of the class described comprising a box open at the upper end, a cover therefor, an inner casing centrally mounted in said box and extending upwardly to said cover, said inner casing being provided over the entire area thereof with closely spaced openings and an ice pan arranged to close the upper end of said casing.

2. A refrigerator of the class described, comprising in combination a box open at the upper end, a cover therefor a relatively smaller box-like lining secured in said box, said lining extending upwardly to the top of said box and provided over its entire area with a plurality of openings, an ice pan supported in the upper end of said casing and a plurality of trays positioned in superposed relation below said ice pan.

3. A refrigerator of the class described including in combination, an outer box, an inner lining arranged therein so as to provide an ice space between the box and the lining, a cover for said box, said lining extending upwardly to said cover, and enlarged adjacent the upper end thereof to provide a support for an ice pan, a pan in said enlarged upper end, a plurality of trays arranged in superposed relation below said ice pan, each of said trays composed of open work material, a plurality of ventilating tubes extending through said box into said lining and regulatable means to open and close said tubes.

In testimony whereof I have hereunto set my hand.

PERRY VACATOS.
